(57) **CLAIM**

The ornamental design for a biometric data storage device, as shown and described.

DESCRIPTION

FIG. 1 is a front perspective view of a first embodiment of a biometric data storage device showing our new design; FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a bottom perspective view thereof;

FIG. 9 is a front perspective view of a second embodiment of a biometric data storage device showing our new design; FIG. 10 is a front view thereof;

FIG. 11 is a rear view thereof;

FIG. 12 is a right side view thereof;

FIG. 13 is a left side view thereof;

FIG. 14 is a top view thereof;

FIG. 15 is a bottom view thereof;

FIG. 16 is a bottom perspective view thereof;

FIG. 17 is a front perspective view of a third embodiment of a biometric data storage device showing our new design; FIG. 18 is a front view thereof;

FIG. 19 is a rear view thereof;

FIG. 20 is a right side view thereof;

FIG. 21 is a left side view thereof;

FIG. 22 is a top view thereof;

FIG. 23 is a bottom view thereof; and,

FIG. 24 is a bottom perspective view thereof.

The broken lines immediately adjacent to the shaded area represent unclaimed boundaries of the design. The broken lines of the biometric data storage device in the figures and the unshaded regions therein are for environmental purposes only and form no part of the claimed design.
